Inventor

L. S. WARD

Townshend & Townshend
By Attorneys.

UNITED STATES PATENT OFFICE.

LEONARD S. WARD, OF VALLEY CITY, NORTH DAKOTA.

LETTER OPENER.

Application filed February 5, 1923. Serial No. 617,023.

To all whom it may concern:

Be it known that I, LEONARD S. WARD, a citizen of the United States, residing at Valley City, in the county of Barnes and 5 State of North Dakota, have invented certain new and useful Improvements in a Letter Opener, of which the following is a specification.

My invention relates to letter opening 10 appliances and has particular reference to a device adapted to be worn on the finger of the user whereby envelopes may be cut and opened in a very efficient manner.

The primary object of the invention is 15 to provide a device of this character in the form of a finger ring equipped with a detachable knife blade for opening envelopes.

Another object of the invention is to provide 20 a device of this character in which the knife blade is equipped with means to anchor it in position against accidental relation when in use.

With these and such other objects in view, as 25 will be apparent from the description, the invention resides in the novel combination, construction and arrangement of parts hereinafter described and claimed and illustrated in the accompanying drawings, in 30 which—

Figure 1 is a perspective of the opener constructed in accordance with my invention;

Figure 2, an end elevation thereof;

Figure 3, a side elevation; and

Figure 4, a detail elevation partly in section illustrating the manner of mounting the cutting blade.

In detail, the device comprises an annular 40 member substantially in the form of a finger ring 1 provided with recessed flanges 2 and 3 on the exterior thereof, which flanges are spaced apart and provided with inturned edges 4 and 5 which are slightly 45 inclined towards the surface of the ring 1. This construction provides in effect a housing in which is adapted to slide the cutting knife 6 extending in a curve from a base 7 slidably in the housing and provided with

50 lateral enlargements 8 and 9 to engage under the inturned edges 4 5 of the flanges 2 and

3. At the base of the shank of the knife 6 is a forwardly extending spur 10 adapted

to lie within the housing and bear against the exterior face of the ring 1. This spur 55 extends in the direction of curvature of the cutting blade and when the blade is in position will effectually prevent any bending or lateral displacement of the blade.

The blade being readily detachable may 60 be removed and sharpened as desired, which will ensure a maximum service with the greatest amount of efficiency in a device of this character, and, while I have illustrated and described certain details entering into 65 the construction of this invention I desire it to be understood that I do not intend these as limitations, but that such may be used as will fall within the scope of the 70 invention as claimed.

As illustrated in Figure 3, the blade is sharpened only through a portion of its length, from the base up to the curved part thereof, the remainder being unsharpened. This is a particular advantage in cutting 75 thick envelopes, cord and the like.

I claim:

1. A device of the character described comprising an annular band adapted to be worn on the finger of the user, upstruck 80 flanges on the exterior face of said band, inturned edges on said flanges and disposed in equi-distant spaced relation, a cutting blade, said blade having a curved shank and an enlarged base, said base being disposed between 85 said flanges and underneath said inturned edges, and a spur carried by said base for retaining said blade in position.

2. A device of the character described comprising an annular band adapted to be 90 worn on the finger of the user, a blade projecting radially from the periphery of said band at one end and having a cutting edge on one of its sides, said blade having a laterally curved unsharpened extension 95 extending in a plane parallel with the horizontal axis of said band and terminating in approximately the same plane with the opposite end of the band from which the blade projects, and means for detachably 100 connecting the base of the blade to the band.

In testimony whereof I affix my signature.

LEONARD S. WARD.
